US0D1078418S

(12) **United States Design Patent** (10) **Patent No.:** **US D1,078,418 S**
(45) **Date of Patent:** **** Jun. 10, 2025**

(54) **DIGITAL TORQUE WRENCH**

(71) Applicant: **STANLEY BLACK & DECKER MEA FZE**, Dubai (AE)

(72) Inventors: **Yen Ting Wu**, Taoyuan (CN); **Ko Han Chen**, Taichung (CN); **Chia Cheng Chen**, Taichung (CN); **Yi Tung Chan**, Taichung (CN); **ChihChiang Lee**, Taichung (CN)

(73) Assignee: **Stanley Black & Decker MEA FZE**, Jebel Ali (AE)

(**) Term: **15 Years**

(21) Appl. No.: **29/909,145**

(22) Filed: **Aug. 1, 2023**

(30) **Foreign Application Priority Data**

Feb. 2, 2023 (EM) 015010396-0001

(51) **LOC (15) Cl.** **08-05**

(52) **U.S. Cl.**

USPC **D8/24**

(58) **Field of Classification Search**

USPC D8/24, 107; D10/83

CPC B25B 23/1425

See application file for complete search history.

(57) **CLAIM**

The ornamental design for a digital torque wrench as shown and described.

DESCRIPTION

FIG. 1 is a front perspective view of a digital torque wrench according to the invention.

FIG. 2 is a right side view of the digital torque wrench of FIG. 1.

FIG. 3 is a left side view of the digital torque wrench of FIG. 1.

FIG. 4 is a bottom view of the digital torque wrench of FIG. 1.

FIG. 5 is a top plan view of the digital torque wrench of FIG. 1.

FIG. 6 is a front view of the digital torque wrench of FIG. 1; and,

FIG. 7 is a rear plan view of the digital torque wrench of FIG. 1.

1 Claim, 7 Drawing Sheets
